UNITED STATES PATENT OFFICE

2,049,033

SEAM PRESSING MACHINE

Harry Weisner, Philadelphia, Pa.

Application June 25, 1935, Serial No. 28,248

8 Claims.

(Cl. 68—9)

This invention relates to seam pressing machines, that is to say, to machines adapted to press down the loose edges of the seams of garments, which seams are formed by the stitching together of pieces of material such as cloth.

More specifically considered, the invention contemplates certain improvements in the machine described in my previous Letters Patent No. 1,955,664, dated April 17, 1934, although it should be understood that certain of the features of the present invention may be applied as well to other types of seam pressing machines.

The principal object of the present invention is to provide a seam pressing machine of simple and efficient character, which is particularly adaptable for pressing seams of garments and the like, and which may be operated by persons having relatively little skill.

A further object of the invention is to provide improved means for applying heat and moisture to the seam portions of a garment while the same are being pressed.

A further object of the invention is to provide improved means for opening and flattening the edge portions of a garment seam as the same are fed to the pressing rolls of the machine.

A further object of the invention is to provide, in a machine of the type shown in my previous Letters Patent hereinbefore referred to, certain improved details of construction whereby the same may be operated more efficiently.

The nature and characteristic features of the invention will be more readily understood from the following description, taken in connection with the accompanying drawings forming part hereof, in which:

Figure 1 is a side elevational view of a seam pressing machine embodying the main features of the present invention;

Fig. 2 is a rear elevational view thereof;

Fig. 3 is an enlarged front elevational view of a portion of the machine, illustrating more particularly the pressing rolls and certain of the parts associated therewith;

Fig. 4 is a perspective view illustrating in detail a portion of the means for opening, spreading, and flattening the edge portions of the garment seam to be operated upon the pressing rolls;

Fig. 5 is a side elevational view of the machine, this view being taken from the side opposite that of Fig. 1;

Fig. 6 is a detail view illustrating a portion of the piping used for conveying steam to one portion of the machine for the purpose of moistening the seam portions of the garment; and

Fig. 7 is a view partly in section and partly in elevation, further illustrating the construction and arrangement of the pressing rolls and certain of the parts associated therewith.

It will, of course, be understood that the description and drawings herein contained are illustrative merely, and that various modifications and changes may be made in the structure disclosed without departing from the spirit of the invention.

In the drawings, 10 is the framework of the machine. A table top 11 is supported by the framework 10. A bracket arm 12 is supported at the upper rear portion of the framework, and extends upwardly and outwardly over the table 15 top 11. Bearings 13 and 14 are carried at the front end of the bracket arm 12.

The upper pressing roll 15 is journaled in the bearings 13 and 14. A bevel gear 18 is fixed on the end of one of the spindles of the pressing roll 15. A bevel pinion 19 meshes with the bevel gear 18.

The bevel pinion 19 is mounted on the front end of a horizontal shaft 20, which is journaled in suitable bearings 21 and 22. The bearings 21 and 22 are secured to or integral with the bracket arm 12. The rear end of the shaft 20 is provided with a driving sprocket 23. A drive chain 24 extends over the sprocket 23, being actuated by a sprocket 25 mounted on the driven shaft 26 of a speed reduction gear 27. The speed reduction gear 27 is in turn driven by an electric motor 28.

The bracket arm 12 is provided, near its lower inner end, with an ear 29, which serves as a means of pivotal support for a lever 30, which projects forwardly and carries the lower pressing roll 31 at its front end.

The lever 30 preferably consists of two parallel bars, arranged one on each side of the lower portion of the bracket arm 12, and the pressing roll 31 is mounted between the front end portions of the two bars constituting said lever. The lever 30 also has an arm 32 projecting rearwardly, behind its point of pivotal support in the ear 29, and the free end of this rearwardly extending arm 32 is pivotally connected to one end of a connecting rod 33, the other end of which is pivotally connected to the rearwardly extending portion of a pivoted foot lever 34. The front end of the lever 34 is provided with a foot plate or pedal 34a.

The connecting rod 33 also preferably consists of two parallel bars arranged one on each side of the respective ends of the bars which constitute the rearwardly extending arm 32 of the lever 30.

The foot lever 34 is pivoted as at 35 to a por-

- tion of the framework 10 of the machine. A coil spring 36 has one end connected as at 37 to a bracket 38 carried by the framework of the machine, and has its other end connected to the 5 rearwardly extending arm 32 of the lever 30 which carries the lower pressing roll 31. The coil spring 36 is preferably positioned within the space between the two bars constituting the connecting rod 33.
- 10 The foregoing arrangement is such that the lower pressing roll 31 is normally held against the upper pressing roll 15 under the tension of the spring 36, being adapted to be retracted therefrom when the front end of the foot lever 34 is 15 depressed.

- For the purpose of opening, spreading, and flattening the seam portions of the garment, there is provided mechanism which is illustrated more particularly in Figs. 3 and 4 of the drawings.
- 20 The same comprises a plow-like device 40 having a narrow vertical front edge portion 41 adapted to enter between the two free edge portions of the seam. The plow-like device 40 is spread toward the rear, and has a flat under surface 42 against which the edge portions of the seam are 25 opened and spread flat.

- The plow-like device 40 is positioned immediately in front of the contacting portions of the rolls 15 and 31, and is carried by a U-shaped member 43, the leg portions 44 of which are slidably mounted in lugs 45 carried by the bearing portions 13 and 14 of the bracket arm 12. Coil springs 46, mounted on the upper ends of the legs 44, normally serve to hold the plow member 35 40 in proper position with respect to the pressing rolls, yet permit the same to be elevated if greater thickness of the cloth is encountered, as, for example, when cross-seams pass thereunder.

- Collars 47, mounted on the leg portions 44 of 40 the U-shaped member 43, beneath the springs 46, serve to limit the downward movement of the U-shaped member 43 and the plow member 40 carried thereby.

- Arranged in front of the lower pressing roll 31 45 is a curved plate 49, which may be secured by side ears 48 to the front end of the lever 30. This plate 49 serves as a means of support to permit the operator to guide the seam portion of the garment to the plow-like spreading member 40 immediately before said seam portion is engaged between the pressing rolls 15 and 31.

- The means for applying heat and moisture to the seam portion of the garment as the same is being pressed will now be described.
- 50 A live steam supply pipe 50 is provided, which extends to a stuffing box 51 mounted on the end of the spindle of the upper pressing roll 15, outside of the bearing 13. The stuffing box 51 provides a means of communication to the hollow 55 interior of the upper pressing roll 15, whereby the live steam supplied through the pipe 50 may cause said pressing roll to be heated to the proper degree. A valve 52 is mounted in the pipe 50, which valve serves to regulate the quantity of steam supplied to the upper pressing roll 15.

- The stuffing box 51 also has connected therewith an outlet pipe 53, a siphon-like extension 54 of which passes into the hollow interior of the upper pressing roll 15, terminating at a point 70 near the bottom thereof. The outlet pipe 53 serves to draw off the water of condensation which will be forced into said pipe by the pressure of the live steam which is supplied through the pipe 50. The pipe 53 extends rearwardly and downwardly to a steam trap 55 provided at the

rear of the machine, so that such of the condensation water as passes to the steam trap 55 may be permitted to escape into a drain pipe 56.

A branch pipe line 57 extends from the pipe 53, forwardly, upwardly, and over the top front 5 of the upper pressing roll 15, where it terminates in a flattened nozzle 58. A control valve 59 is mounted in the pipe 57 to regulate the amount of steam which passes through the nozzle 58. The nozzle 58 is provided to moisten the upper 10 face of the seam portion of the garment.

Steam is also supplied to the under face of the seam portion of the garment by means of a flattened nozzle 60, which extends around in front of the lower pressing roll 31, terminating immediately below the plow member 40. Steam is supplied to the lower nozzle 60 by means of the pipe 61 which extends rearwardly between the two bars constituting the lever 30.

The pipe 61 extends first in proximity to the 20 point of pivotal connection of the lever 30, thence downwardly as at 62 to a swivel joint 64, by means of which it is connected to an arm portion 63, which is connected by elbow connections to another arm portion 65, which is connected by an 25 other swivel joint 66 to the downwardly extending pipe 67. The pipe 67 is connected by a horizontally extending pipe 68 to the pipe 53 which extends from the upper pressing roll 15 to the steam trap 55. A control valve 69 is provided in 30 the pipe 61 near the nozzle portion 60 thereof, for regulating the amount of steam supplied to the under face of the seam portion of the garment.

It will be noted that, by the foregoing arrangement, the moistening nozzles 58 and 60 are connected to the return pipe line 53, whereby the steam which will be supplied to said nozzles will be at substantially the condensation point, so that the proper moistening effect will be obtained. However, any water of condensation which may 40 accumulate in the piping which extends to the moistening nozzles will be released through the steam trap 55.

The manner of operation of the machine will be readily apparent.

When it is desired to use the machine, the steam is first admitted to the upper pressing roll 15 until said roll is sufficiently heated, whereupon the machine will be ready to have the seam portion of the garment fed thereto.

The operator will then depress the foot lever 34, causing the lower pressing roll 31 to be separated from the upper pressing roll 15. The operator will, at the same time, open the valves 59 and 69 for supplying the steam to the moistening 55 nozzles 58 and 60, respectively. The garment with the seam to be pressed is then placed in the proper position between the rolls 15 and 31. The foot lever 34 will then be released, permitting the lower pressing roll 31 to press the seam portion 60 of the garment against the upper pressing roll 15, causing the garment to be fed between said pressing rolls 15 and 31, the seam being opened and spread flat by the plow member 40 as the same is advanced; and the moistening steam is at the 65 same time supplied to both the upper and lower faces of the garment by the nozzles 58 and 60.

It will be noted that the machine hereinbefore described will be particularly adaptable for the pressing of tubular articles such as sleeves and trouser legs. In the use of the machine for such purpose, the tubular article is passed over the lever 30 as the pressing progresses, but after the pressing has been completed, the article may be withdrawn by depressing the foot lever 34 to sepa- 75

rate the lower pressing roll 31 from the upper pressing roll 15.

I claim:

1. In a machine for pressing seams of garments and the like, a main pressing roll journaled at a fixed location, means for rotating said pressing roll, a retractable auxiliary pressing roll arranged adjacent the main pressing roll, one of said pressing rolls having a hollow interior, a steam supply pipe connected to supply steam to the interior of said pressing roll to heat the same, a return pipe adapted to drain condensation water from the interior of said pressing roll, a moistening nozzle having an outlet in front of the main pressing roll, and another moistening nozzle movable in unison with the auxiliary pressing roll and having an outlet in front of said roll, and pipe connections between said return pipe and said moistening nozzles to supply moistening fluid to said nozzles.

2. In a machine for pressing seams of garments and the like, a main pressing roll journaled at a fixed location, means for rotating said pressing roll, a retractable auxiliary pressing roll arranged adjacent the main pressing roll, one of said pressing rolls having a hollow interior, a steam supply pipe connected to supply steam to the interior of said pressing roll to heat the same, a return pipe having an extension projecting into the lower portion of the interior of said pressing roll and adapted to drain condensation water therefrom, said return pipe extending to a steam trap, a moistening nozzle having an outlet in front of the main pressing roll, a pipe extending from said return pipe to said nozzle for supplying steam thereto, another moistening nozzle movable in unison with the auxiliary pressing roll and having an outlet in front of said roll, and a pipe having swivel joints interposed therein, said pipe extending from said return pipe to said nozzle for supplying steam thereto.

3. In a machine for pressing seams of garments and the like, a main pressing roll journaled at a fixed location, means for rotating said pressing roll, a retractable auxiliary pressing roll arranged adjacent the main pressing roll, one of said pressing rolls have a hollow interior, a steam supply pipe connected to supply steam to the interior of said pressing roll to heat the same, a return pipe having a fixed extension projecting into the lower portion of the interior of said pressing roll and adapted to drain condensation water therefrom, said return pipe extending to a steam trap, a moistening nozzle having an outlet in front of the main pressing roll, a pipe connecting said nozzle to the aforesaid return pipe to supply steam to said nozzle, another moistening nozzle movable in unison with the auxiliary pressing roll and having an outlet in front of said roll, and a pipe having swivel joints interposed therein

connecting said nozzle to the aforesaid return pipe to supply steam to said nozzle.

4. In a machine for pressing seams of garments and the like, a main pressing roll journaled at a fixed location, means for rotating said pressing roll, a retractable auxiliary pressing roll arranged adjacent the main pressing roll, one of said pressing rolls having a hollow interior, a steam supply pipe connected to supply steam to the interior of said pressing roll to heat the same, a return pipe having a fixed extension projecting into the lower portion of the interior of said pressing roll and adapted to drain condensation water therefrom, a moistening nozzle having an outlet in front of the main pressing roll, means for supplying steam from said return pipe to said nozzle, another moistening nozzle movable in unison with the auxiliary pressing roll and having an outlet in front of said roll, and means for supplying steam from said return pipe to said nozzle.

5. In a machine for pressing seams of garments and the like, a hollow pressing roll, a live steam supply pipe connected to supply steam to the interior of said pressing roll to heat the same, a return pipe adapted to drain condensation water from said roll, said return pipe extending to a steam trap, a moistening nozzle having an outlet in front of said pressing roll, and a pipe connecting said nozzle to the aforesaid return pipe.

6. In a machine for pressing seams of garments and the like, a pressing roll journaled at a fixed location, means for rotating said pressing roll, an auxiliary pressing roll arranged adjacent the main pressing roll, a retractable lever on which said auxiliary pressing roll is mounted, a guide plate mounted on said lever, and a plow-like device for spreading the seam edges arranged adjacent said plate.

7. In a machine for pressing seams of garments and the like, a pressing roll journaled at a fixed location, means for rotating said pressing roll, an auxiliary pressing roll arranged adjacent the main pressing roll, a retractable lever on which said auxiliary pressing roll is mounted, a guide plate mounted for movement with said lever, and a resiliently supported plow-like device for spreading the seam edges arranged adjacent said plate.

8. In a machine for pressing seams of garments and the like, a pressing roll journaled at a fixed location, means for rotating said pressing roll, a retractable auxiliary pressing roll arranged adjacent the main pressing roll, a retractable lever on which said auxiliary pressing roll is mounted, a guide plate mounted on said lever, and a resiliently supported plow-like device for spreading the seam edges disposed rearwardly of said plate and in front of said pressing rolls.

HARRY WEISNER.
